(57) **CLAIM**

The ornamental design for a child seat for motor cars, as shown and described.

DESCRIPTION

1. Child seat for motor cars

1.1 is a perspective view of a child seat for motor cars in accordance with the present invention;

1.2 is a side elevational view of a first side of the child seat of 1.1;

1.3 is a side elevational view of a second side of the child seat of 1.1;

1.4 is a front elevational view of the child seat of 1.1;

1.5 is a rear elevational view of the child seat of 1.1;

1.6 is a top plan view of the child seat of 1.1; and

1.7 is a bottom plan view of the child seat of 1.1.

The broken lines in the drawings depict portions of the child seat for motor cars that form no part of the claim.
